EDWARD S. MARSH, OF ROCHESTER, NEW YORK.

CONTROLLING MECHANISM FOR TALKING-MACHINES.

1,307,014.

Specification of Letters Patent. Patented June 17, 1919.

Application filed October 18, 1915. Serial No. 56,424.

To all whom it may concern:

Be it known that I, EDWARD S. MARSH, of Rochester, in the county of Monroe, State of New York, have invented a new and useful Controlling Mechanism for Talking-Machines, which invention is fully set forth in the following specification and shown in the accompanying drawings.

The present invention relates to controlling mechanisms for talking machines and more particularly to the type provided with means for automatically effecting the stopping of the machine when the stylus has reached the end of the record, an object of this invention being to provide an electrical stop which does not employ the tone arm as part of the circuit.

Another object of the invention is to provide an improved controlling means having a circuit closer which is shiftable to any desired position of the face of the record for the purpose of effecting the automatic stopping of the machine at the desired point.

To these and other ends the invention consists in certain parts and combinations of parts all of which will be hereinafter described, the novel features being pointed out in the appended claims.

In the drawings:

Figure 1 is a fragmentary top view of the talking machine in which the present invention is embodied;

Fig. 2 is a diagram showing the brake operating mechanism and the circuit controlling the same;

Fig. 3 is a detail view in section of the circuit closer;

Fig. 4 is a vertical section in the direction of the axis of the eccentric brake;

Fig. 5 is a detail sectional view of the mounting of the circuit closer;

Fig. 6 is a detail sectional view of the device for shifting the brake from braking position;

Fig. 7 is a detail view showing the brake-operating magnet in side elevation; and

Fig. 8 is a detail view of the circuit closer for stopping the machine independently of the one engaged by the reproducer.

In the embodiment of the invention herein illustrated 1 indicates a table above which a record support 2 is mounted and on the under side of which a motor 3 of any suitable construction is arranged for turning the record support. A record 4 is supported on the record support 2 and is adapted to be

engaged by the stylus 5 on the reproducer 6, the latter being supported on a tone arm 7 of any suitable construction.

The stop for the motor comprises a brake 60 preferably in the form of an eccentric 8 having a yielding portion 9 and carried by a shaft 10 so as to move into and out of cooperative relation with the rotary record support 2. This brake preferably has a normal tendency to move to braking position and this tendency may be produced by a spring 11 anchored at one end 12 to a bracket 13 and at the other end at 14 to an arm 15 which is secured to the shaft 10 65 of the brake. To hold the brake out of braking position a latch 16 may be employed pivoted at 17 and controlled by an electro-magnet 18 whose armature 19 is connected to an arm of the latch 16, the latch being 70 moved into latching engagement with the arm 29 of the brake under the action of a spring 20 that is mounted on the bracket 13 and co-operates with such latch.

The electro-magnet 18 may be energized 80 by a battery 21 and may be controlled by a plunger switch 22 arranged on the under side of the table 1 and having an operating plunger 23 extending through the table to the top thereof, the depression of the 85 plunger causing the closing of the circuit 24 which leads to the electro-magnet. It is desirable to break the circuit 24 after the electro-magnet has been energized to operate the brake, and to this end the arm 15 of the 90 brake on the brake shaft 10 is connected to the circuit 24 and co-operates with a contact 25 when the brake is out of braking position but moves out of engagement with the contact 25 when the brake moves into braking position, thus breaking the circuit 24. The brake or stop 8 may be moved out of engagement with the record support 2 preferably by a spring pressed plunger 26 operating through the table 1 and co-operating with a bell crank 100 lever 27 which is pivoted at 28 to the under side of the table. This bell crank lever bears against the arm 15 on the brake shaft 10 so that, with the depression of the plunger 26, the bell crank lever will shift the arm 15 105 until the latch 16 co-operates with the arm 29 on the shaft 10 of the brake or stop, thus at the same time causing the closing of the break in the circuit produced by the arm 15 of the brake shaft.

There may also be provided means for automatically stopping the machine when the

end of the record is reached. This means preferably embodies an arm 30 carrying two contacts 31 and 32 at its outer end and mounted to swing on a pivot 33 about an 5 axis perpendicular to the plane of the record, so that the arm may move over the record, said arm being also mounted to swing about an axis 34 parallel with the plane of the record so that the arm may move toward 10 and from the record for the purpose of permitting the finder point 35 formed on one of the contacts 32 to be engaged with the record. A spring washer 36 with a laterally extending spring arm 37 serves the dual function 15 of producing friction to restrain the movement of the arm about the pivot 33 and to hold the arm away from the record 4.

The finder 35 is adapted to enter the groove of the record when the arm is moved 20 toward the record so that the arm may be positioned over the record at any point where it is desired that the machine shall stop. The most desirable stopping point will be the end of the groove and this point 25 will be obtained by pressing the arm 30 toward the record and permitting the record to rotate. This causes the finder point 35 to travel in the groove until the end of the latter is reached. At this time, the arm 30 is freed and will lie above the record at a 30 point where the machine is to be stopped. During the operation of the machine the stylus will travel in the groove in the usual manner until it engages the contact 31. This 35 effects the closing of the circuit 24 through

the shunt circuit 24^a and the energizing of the magnet 19 thus releasing the brake 8 and permitting the latter to turn into engagement with the rotary record support 2. The starting of the machine is effected by 40 depressing the plunger 26 thus freeing the record support 2 to the motor 3. It is apparent also that the machine may be stopped at any point by depressing the plunger 23 which will also effect the closing of the circuit 24 and operation of the brake 8 into 45 cooperation with the rotary record support 2.

It is apparent that an automatic electrical stop has been provided for stopping the machine at the end of a record groove without 50 utilizing the tone arm as part of the circuit of the electrical circuit.

What I claim as my invention and desire to secure by Letters Patent is:

1. In a talking machine, the combination 55 with a record support, and a reproducer, and an electrically operated means for controlling the stopping of the record support embodying a make and break device having its two contacts adjustable simultaneously relatively to the reproducer in the path of the reproducer.

2. In combination with a talking machine having a stop device, an automatic controller for such stop device comprising an 60 arm adjustable to different positions over the record relatively to the reproducer, and two contacts carried by the arm in the path of the reproducer.

EDWARD S. MARSH.
